GOVERNOR

Eldon B. Heft, North East, Pa., assignor to General Electric Company, a corporation of New York

Application December 23, 1955, Serial No. 555,002

16 Claims. (Cl. 123—103)

This invention relates to an engine governor and more particularly to a speed responsive fuel rate mechanism for a governor applicable to a diesel electric locomotive engine.

With the advent of the diesel locomotive, various speed responsive governors have been designed to accelerate the diesel engine when extra power is required to accelerate the train. These governors are low inertia devices which respond quickly to speed signals from the engine. Thus, in the event of an increased power demand as indicated by a decrease in the engine speed signal, the governor supplies more fuel to the engine to increase and maintain its speed. However, during such engine acceleration, fuel may be supplied to the engine at a rate greater than the combustion rate. This excessive fuel rate invariably results in "acceleration" smoke and often results in damage to the internal engine parts.

Therefore, an object of my invention is to provide a simple and reliable speed responsive governor which prevents smoking by limiting the supply of fuel to that required by the engine.

A further object is to provide a governor especially adapted to the engine acceleration characteristic for controlling the rate of supply of fuel.

In carrying out my invention in one form, the governor is provided with a time delay means to match the inertia of the particular engine being accelerated. When acceleration is called for by a decrease in speed of the engine, the governor increases the supply of fuel to the engine at a predetermined rate. If an increase in the load in the engine causes a predetermined engine slow down, the governor removes a portion of the load to provide for rapid increase of the engine speed.

Further objects and advantages of my invention will be better understood by reference to the following detailed description and the accompanying drawings. The features of novelty will be pointed out with particularity in the claims annexed to and forming part of this specification.

In the drawings,

Fig. 1 is a vertical sectional view of my governor showing the main operating parts at the start of the acceleration cycle;

Fig. 2 is a vertical sectional view of my invention during load control acceleration;

Fig. 3 is a vertical sectional view of my invention during the reset cycle; and

Fig. 4 is a fragmentary view showing modifications of my improved governor.

Referring now to the drawings in which like numerals refer to similar parts, I have shown one embodiment of my invention in Fig. 1 wherein a governor 1 is provided with an inlet port 2 which supplies a fluid under pressure to the hydraulic system of the governor from a pump or other sources not shown. When the speed of an engine 3 drops because of overloading, a solenoid 4 is energized by a signal from a tachometer 5. The solenoid 4

2

is connected to move a valve member 6 to the position shown in Fig. 1 to open the inlet port 2. This admits the fluid under pressure to a passage 7 which commutes through a port 8 with a piston 9. At the same time, fluid pressure is applied from the passage 7 through a needle valve 10 to another piston 11.

The pressure of the fluid admitted through the inlet port 2 is sufficient to move the piston 9 upward with the fluid above the piston 9 passing out through a passage 12 and a port 13. Movement of the piston 9 rotates a gear 14 and an attached shaft 15. The shaft 15 is connected at one end to an operating arm 18 which normally rests against a stop member 19 and at the other end to a variable voltage tap or brush 20 of a voltage divider or rheostat 21. A load control spring 22, having an end 23 connected to the stop member 19, is tensioned between the stop member 19 and the shaft 15 to force the operating arm 18 against the stop 19. In order to allow a more rapid acceleration of the diesel engine 3, a load control means shown as the rheostat 21 is connected in the generator exciter circuit (not shown) to reduce the excitation of the generator and thus the load on the diesel engine during the acceleration. I prefer that this occur only under a "load control" condition to be explained more fully below. In the particular arrangement I have shown, I prefer that the spring 22 starts to wind up only after 80 p. s. i. hydraulic pressure is applied to the piston 9. Thus, it is readily apparent that the spring 22 biases the piston 9 toward the position shown in Fig. 1.

30 However, the piston 11 requires a fluid pressure of only 65 p. s. i. to start the piston 11 moving downward against the bias of a spring 24 and 80 p. s. i. to completely compress the spring 24. This movement of the piston 11 rotates the gear 16 and the shaft 17 to rotate a stop means such as a cam 25 at a speed dependent on the fluid pressure and the opening of the needle valve 10. Brush pressure under the piston 11 is released by an oil drain 27.

35 In operation, when the engine 3 is running at too low a speed and more power is required, the valve 6 is moved upward by a signal from the tachometer 5 to admit fluid to force the piston 9 upward, rotating the shaft 15 to increase the fuel by causing a counterclockwise rotation of a cam follower lever arm 26. This rotation causes a shaft 28 to rotate and a fuel control valve arm 29 to move the fuel supply means or racks 30 toward the full fuel position until a cam follower 31 engages the cam stop 25. Thus, the piston 9 drives the fuel racks 30 through the linkage 18, 19, 22, 23, 26, 28, 29 when the cam follower 31 is not stopped by engagement of the cam 25.

40 When the cam follower 31 engages the cam 25, further movement of the piston 9 is prevented by the tensioned load control spring 22 until the pressure in the passage 7 reaches 80 p. s. i., at which time the piston 9 continues to move upward against the bias of the spring 22 thereby forcing the governor into "load control" by further compressing the spring 22. This further compression of the spring 22 is shown in Fig. 2, where the operating arm 18 is moved clockwise enough to provide a gap between the end thereof and the stop member 19. Thus, the signal is stored in the spring 22 until the valve 10 allows the signal to be transferred to the piston 11 and the cam 25 at which time the operating arm 18 again engages the stop 19 as shown in Fig. 3. During "load control" the brush 20 is moved into the active section of the rheostat 21 which reduces the generator voltage allowing the engine speed to increase rapidly under a decreased load.

45 As mentioned above, a hydraulic pressure greater than 65 p. s. i. in the passage 7 causes fluid to be metered

through the needle valve 10, forcing the piston 11 down against the spring 24 and rotating the gear 16, the shaft 17 and the cam 25 at a predetermined rate. It should be noted that the area surrounding the spring 24 is provided with the oil drain 27 which prevents any leakage oil from collecting therein to provide a back pressure under the piston 11. As the cam 25 rotates, the cam follower 31 will allow the fuel control valve arm 29 to be moved to the left by the tensioned load control spring 22 thereby increasing the fuel admission to the diesel engine 3 at a predetermined rate. Thus, when the cam follower 31 engages the cam 25, the spring 22 is further tensioned by continued upward movement of piston 9 and engine speed is allowed to increase more rapidly because of the reduced load during load control. I prefer that this linkage be designed so that only a few degrees rotation of the stop member 19 is required to drive the fuel racks 30 from idle to full fuel.

When the engine speed reaches a predetermined desired value, the valve 6 will close the inlet port 2 (Fig. 2) in response to a signal from the tachometer 5. At this time with a gap between the operating arm 18 and the stop member 19, the load control spring 22 requires 80 p. s. i. pressure to remain tensioned while the spring 24 requires only 65 to 80 p. s. i. to be moved a full stroke. In order to increase the generator voltage to its normal value while maintaining the desired engine speed, the spring 22 will unwind the stored signal, returning the piston 9 downward toward its normal unbiased position and transferring fluid through the passage 7 and the needle valve 10 to move the piston 11 in the downward direction. In order to allow movement of the piston 9 without creating a vacuum above it when the valve 6 is closed, I prefer that the valve 6 allow a slight seepage from the inlet port 2 to enter the passage 12.

As the piston 11 is driven downward, the cam 25 rotates toward the full fuel position as shown in Fig. 3. At the same time, since only a few degrees rotation of the spring 22 is required to drive the fuel racks 30, the piston 9 and the shaft 15 will be returned sufficiently to allow the brush 20 of the rheostat 21 to be returned from the "load control" position to the full excitation position. In order to maintain the speed of the engine nearly constant during the recovery from "load control," the fuel as controlled by the cam 25 and the load as controlled by the rheostat 21 are increased at a proportional rate, and the piston 11 stops at the time the operating arm 18 engages the stop member 19.

When it is desired to reduce the engine speed and reset the governor, an overspeed signal is provided by the tachometer 5 and the valve 6 is moved from the position shown in Fig. 2 downward to the position shown in Fig. 3. This increases the pressure in the line 12 by connecting the inlet port 2 thereto and reduces the pressure in the line 7 by opening an exhaust port 32. The piston 9 is moved downward by the pressure in the line 12. At the same time, the piston 11 is forced upward by the spring 24 to force the fluid out through the needle valves 10 and 33. The back pressure on the needle valve 33 forces a check valve ball member 34 downward to open this valve and allow the passage of fluid therethrough and reset the governor.

By the use of my invention, the time required to advance the fuel racks from one position to another may be either linear or variable by proper contouring of the cam 25. Thus, the governor may be made to operate satisfactorily with any type of diesel engine. For instance, if a diesel engine tends to smoke less during acceleration at medium speeds than during acceleration at high or low speeds, the contour of the cam 25 can be made to allow an acceleration or fuel increase in the range of the medium speeds more rapidly than at the high or low speeds.

Also with this simple hydraulic governor, the fuel advance rate may be varied by adjusting the needle valve 10 to meet all operating conditions. I prefer that the needle valve 10 be set to provide slower acceleration for passenger locomotives thus completely eliminating engine "acceleration" smoke. For moderate acceleration necessary for freight service, the needle valve may be set at an intermediate position. For switching service where rapid acceleration is essential, the needle valve should be opened more fully.

Also, with my invention the reset time can be adjusted by moving the needle valve 33 depending upon the service required from the locomotive.

In many locomotive jobs the use of the locomotive is determined before it is built so that the adjustable features of the needle valves 10 and 33 are not necessary. Also, it has been found that the temperature rating in service in locomotives is such that the viscosity of the fluid passing through the needle valves greatly affects the rate of flow. Therefore, in Fig. 4 I have shown the valves 38 and 39 wherein a series of thin plates 40 each containing a small axial orifice to accurately limit the flow of the hydraulic fluid to the specified amount as the temperature of the hydraulic fluid varies over a wide range.

These thin plates eliminate a relatively large area of the film which forms a part of the orifice in such devices as needle valves. This film is eliminated mainly by the fact that the surface of the orifice is small compared to the area thereof while the surface involved in a needle valve of the same capacity is much greater. Since the viscosity of this film varies with fluid temperature, the setting of any needle valve is varied, causing variation in the control of the acceleration depending on the fluid temperature. Of course, it would be necessary to vary the number of plates for a particular locomotive, putting in more plates for the passenger locomotive, fewer plates for the freight locomotive, and the least number of plates for the switcher locomotive, thus allowing the minimum of smoke for the passenger locomotive and a greater amount of smoke for the switcher locomotive where it is not as offensive to the customers of the railroad.

I have found that after the valve 6 closes the inlet port 2 as shown in Fig. 2, it sometimes occurs that the valve 6 does not move to the position shown in Fig. 3 as rapidly or for as long a period as desirable. In order to prevent smoking because of space between the cam 25 and the cam follower 31, by allowing the spring 24 to force a limited amount of fluid out the valve 42 when the fuel racks 30 have been moved to a position which reduces the fuel one or more steps or notches. This valve 42 will not effect a change in the setting of fuel racks because of the fact that with this modification the spring 24 is designed to provide less tension than would be necessary to move the fuel racks back when the cam 25 engages the cam follower 31 or to force enough fluid into the line 7 to move the piston 9 and the fuel racks 30 ahead when the cam 25 does not engage the cam follower 31.

While I have shown and described particular embodiments of my invention, modifications thereof will occur to those skilled in the art. Therefore, I intend by the appended claims to cover all such modifications as come within the true spirit and scope of my invention.

What I claim as new and desire to secure by Letters Patent of the United States is:

1. A governor for regulating the acceleration of an engine comprising a first relatively high speed hydraulic operating means, a second hydraulic operating means having a relatively low speed matching the acceleration of the engine, a common control valve for said operating means arranged for operation in response to a decrease in the speed of the engine to cause movement of said operating means, driving means including a

movement storage spring for connecting said first operating means to a fuel supply means of the engine for operation to increase the supply of fuel to the engine, movable stop means cooperating with said driving means to limit the movement of said driving means and of said fuel supply means to a predetermined amount after which continued movement of said first operating means is stored in said spring, and a driving connection between said second operating means and said stop means for moving said stop means to provide for movement of said fuel supply means by said spring.

2. A governor for regulating the acceleration of an engine comprising a first relatively high speed hydraulic piston, a second hydraulic piston having a relatively low speed matching the acceleration of the engine, means biasing said pistons to predetermined positions, a common control valve for said pistons arranged for operation in response to a decrease in the speed of the engine to cause movement of said pistons, a linkage including a movement storage spring for connecting said first piston to a fuel supply means of the engine for operation to increase the supply of fuel to the engine, movable stop means cooperating with said linkage to limit the movement of said linkage and of said fuel supply means to a predetermined amount after which continued movement of said first piston is stored in said spring, and a driving connection between said second piston and said stop means for moving said stop means to provide for movement of said fuel supply means by said spring.

3. A governor for regulating the acceleration of an engine comprising a relatively high speed hydraulic operating means, a second hydraulic operating means having a relatively low speed matching the acceleration of the engine, a common control valve for said operating means arranged for operation in response to a decrease in the speed of the engine to cause movement of both of said operating means, a linkage for connecting said first operating means to a fuel supply means of the engine for operation of said fuel supply means to increase the supply of fuel to the engine, said linkage including a spring for storing movement of said first operating means, movable stop means cooperating with said linkage to limit the movement of said linkage and said fuel supply means to a predetermined amount after which continued movement of said first operating means is stored in said spring, and a driving connection between said second operating means and said stop means for moving said stop means to provide for movement of said fuel supply means by said spring.

4. A governor for regulating the acceleration of an engine comprising a first relatively high speed hydraulic operating means, a second hydraulic operating means having a relatively low speed matching the acceleration of the engine, a common control valve for said operating means arranged for operation in response to a decrease in the speed of the engine to cause movement of both of said operating means, a linkage for connecting said first operating means to a fuel supply means of the engine for operation of said fuel supply means to increase the supply of fuel to the engine, said linkage including a spring for storing movement of said first operating means, movable stop means cooperating with said linkage, a driving connection between said second operating means and said stop means for moving said stop means to provide for movement of said fuel supply means by said first operating means, and means for biasing said second operating means and said stop means to a predetermined position in which said stop means limits the movement of said linkage and said fuel supply means to a predetermined amount after which continued movement of said first operating means is stored in said spring.

5. A governor for regulating the acceleration of an engine, comprising a first means responsive to an engine speed signal for increasing the fuel supplied to the engine, a second means cooperating with said first means so as to

prevent an increase in the fuel supply greater than a predetermined rate, hydraulic operating means connecting said first and second means, and means connected to said first means to store said signal and to reduce the load on the engine while said signal is being transmitted to said second means by said hydraulic means.

6. A governor for regulating the acceleration of an engine, comprising a first piston responsive to an engine speed signal for increasing the fuel supplied to the engine, a second piston cooperating with said first piston so as to prevent an increase in the fuel supply greater than a predetermined rate, hydraulic operating means connecting said first and second pistons, and means connected to said first piston to store said signal and to reduce the load on the engine while said signal is being transmitted to said second piston by said hydraulic means.

7. A governor for regulating the acceleration of an engine, comprising a first means connected to a fuel supply means for increasing the fuel supplied to the engine, a second means adapted to prevent an increase in the fuel supply greater than a predetermined rate, hydraulic operating means connecting said first and second means, a valve connected to admit fluid to said hydraulic means in response to a speed signal from the engine, load control means connected to said first means to store said signal from said first means and to reduce the load on the engine until this signal stored is hydraulically transmitted to said second means, and means connected to said hydraulic means for resetting said first and said second means.

8. A governor for regulating the acceleration of an engine, comprising a first piston connected to a fuel supply means for increasing the fuel supplied to the engine, a second piston connected to a cam operator having a cam contour adapted to engage the connection between said first piston and said fuel supply means to prevent an increase in the fuel supplied greater than a predetermined rate, hydraulic operating means connecting said first and second pistons, a valve connected to admit fluid to said hydraulic means in response to a signal from the engine, load control means connected to said first piston to be energized by movement of said first piston and to reduce the load on the engine until said first piston is returned to a predetermined position and means for resetting said first and said second pistons.

9. A governor for regulating the acceleration of an engine comprising, a first piston, connections connecting said first piston to a fuel supply means for increasing the fuel supplied to the engine, a second piston connected to a cam operator having a cam contour adapted to engage said connections to prevent an increase in the fuel supplied greater than a predetermined rate, a hydraulic system connecting said first and second pistons, a valve connected to admit fluid under pressure to said hydraulic system and adapted to be energized by a speed signal from the engine whereby fuel to the engine is increased in response to said signal, a fluid restriction connected in said hydraulic system to retard the movement of said second piston, a load control spring connected to said first piston to be energized by movement of said first piston, a load control means operably connected to said first piston to reduce the load on the engine until said first piston is returned to a predetermined position and means connected in said hydraulic system for resetting said first and said second pistons.

10. A governor for regulating the acceleration of an engine, comprising a first piston, a connection connected between a fuel supply means and said first piston for increasing the fuel supplied to the engine in response to movement of said first piston, a second piston, a cam connected to said second piston, said cam being adapted to engage said connection between said first piston and said fuel supply means to prevent an increase in the fuel supplied greater than a predetermined rate, a hydraulic system connecting said first and second pistons, a valve connected to admit fluid under pressure to said hydraulic

system and adapted to be energized by a speed signal from the engine whereby fuel to the engine is increased, a needle valve connected in said hydraulic system to retard the movement of said second piston, a load control spring connected in said connection to be energized by movement of said first piston when said cam engages said connection, a load control means operably connected to said first piston to reduce the load on the engine until said first piston is returned by said spring to a predetermined position and means connected in said hydraulic system for resetting said first and said second pistons.

11. A governor for regulating the acceleration of an engine, comprising a first piston, a connection connected between a fuel supply means and said first piston for increasing the fuel supplied to the engine in response to movement of said first piston, a second piston, a cam connected to said second piston, said cam being adapted to engage said connection between said first piston and said fuel supply means to prevent an increase in the fuel supplied greater than a predetermined rate, a hydraulic system connecting said first and second pistons, a valve connected to admit fluid under pressure to said hydraulic system and adapted to be energized by a speed signal from the engine whereby fuel to the engine is increased, a plate having a restricted axial orifice therein connected in said hydraulic system to retard the movement of said second piston, a load control spring connected in said connection to be energized by movement of said first piston when said cam engages said connection, a load control means operably connected to said first piston to reduce the load on the engine until said first piston is returned by said spring to a predetermined position and means connected in said hydraulic system for resetting said first and said second pistons.

12. A governor for regulating the acceleration of an engine provided with fuel racks, comprising a first piston, connections connected between the fuel racks and said first piston for increasing the fuel supplied to the engine in response to movement of said first piston, a second piston, a cam connected to said second piston for engaging said connection to prevent an increase in the fuel supplied greater than a predetermined rate, a hydraulic system connecting said first and second pistons, a valve connected to admit fluid under pressure to said hydraulic system and adapted to be energized by a speed signal from the engine whereby fuel to the engine is increased in response to said signal, a first needle valve connected in said hydraulic system to retard the movement of said second piston in response to fluid pressure in said system, a load control spring connected to said first piston to be energized by movement of said first piston, said spring thereafter biasing said first piston toward its normal position to create a pressure in said hydraulic system sufficient to drive said second piston and rotate said cam, a by-pass line around said restricted plate, a check valve in said line to prevent fluid flow therein to said second piston, and a second needle valve connected in said line for controlling the reset period of said second piston.

13. A governor for regulating the acceleration of an engine provided with fuel racks, comprising a first piston, connections connected between the fuel racks and said first piston for increasing the fuel supplied to the engine in response to movement of said first piston, a second piston, a cam connected to said second piston for engaging said connection to prevent an increase in the fuel supplied greater than a predetermined rate, a hydraulic system connecting said first and second pistons, a valve connected to admit fluid under pressure to said hydraulic system and adapted to be energized by a speed signal from the engine whereby fuel to the engine is increased in response to said signal, a first plate having a restricted axial orifice therein connected in said hydraulic system to retard the movement of said second piston in response to fluid pressure in said system, a load control spring con-

nected to said first piston to be energized by movement of said first piston, said spring thereafter biasing said first piston toward its normal position to create a pressure in said hydraulic system sufficient to drive said second piston and rotate said cam, a by-pass line around said restricted plate, a check valve in said line to prevent fluid flow therein to said second piston, and a second plate having a restricted axial orifice connected in said line for controlling the reset period of said second piston.

14. A governor for regulating the acceleration of an engine provided with fuel racks, comprising a first piston, connections connected between the fuel racks and said piston for increasing the fuel supplied to the engine in response to movement of said first piston, a second piston, a contoured cam operably connected to said second piston for engaging said connections between said first piston and said fuel racks to retard the movement of said connections, a hydraulic system connecting said first and second pistons, a valve connected to admit fluid under pressure to said hydraulic system and adapted to be energized by a signal from the engine whereby fuel to the engine is increased in response to the speed of the engine, a plurality of plates having a restricted axial orifice therein connected in said hydraulic system to retard the movement of said second piston in response to said pressure, a load control spring connected to said first piston for storing the signal from said engine until the signal is hydraulically transmitted to said second piston, said spring being tensioned by movement of said first piston beyond the port where said cam engages said connections, said tensioned spring drivingly connected to said first piston whereby said first piston drives said second piston to rotate said cam and allow an increase in fuel supplied to the engine, a load control means operably connected to said first piston to reduce the load on the engine until said first piston is returned by said spring to said predetermined position, a line connected to by-pass said plates, and a check valve in said line to allow fluid flow in said line from said second piston for resetting said second piston.

15. A governor for regulating the acceleration of an engine provided with a fuel rack, comprising a first piston, means for applying fluid pressure to said first piston, connections operatively connected between the fuel rack and said piston, a second piston, a contoured cam operably connected to said second piston for engaging said connections to prevent an increase in the fuel supplied greater than a predetermined rate, said connections being provided with a load control spring adapted to be tensioned by movement of said first piston when said cam engages said connections, a hydraulic system connecting said first and second pistons whereby said tension on said spring is transferred from said first piston to said second piston, a restriction in said hydraulic system between said first and second pistons to retard the movement of said second piston in response to said tension, means operably connected to said first piston to reduce the load on the engine until said first piston is returned by said spring to a predetermined position, a fluid pressure line connected to by-pass said restriction, and a check valve in said line to allow fluid flow in said line from said second piston for resetting said second piston.

16. A governor for regulating the acceleration of an engine provided with a fuel rack, comprising a first piston, means for applying fluid pressure to said first piston, connections operatively connected between the fuel rack and said piston, a second piston, a contoured cam operably connected to said second piston for engaging said connections to prevent an increase in the fuel supplied greater than a predetermined rate, said connections being provided with a load control spring adapted to be tensioned by movement of said first piston when said cam engages said connections, a hydraulic system connecting said first and second pistons whereby said tension on said spring

is transferred from said first piston to said second piston, a restriction in said hydraulic system between said first and second pistons to retard the movement of said second piston in response to said tension, and means operably connected to said first piston to reduce the load on the engine until said first piston is returned by said spring to a predetermined position.
